DESIGN FOR A SASH WEIGHT SUSPENSION PULLEY COVER

Joseph Niedermeyer, Milwaukee, Wis.

Application September 27, 1944, Serial No. 115,486

Term of patent 14 years

(Cl. D10—10)

To all whom it may concern:

Be it known that I, Joseph Niedermeyer, a citizen of the United States of America, residing at Milwaukee, in the county of Milwaukee and State of Wisconsin, have invented a new, original, and ornamental Design for a Sash Weight Suspension Pulley Cover, of which the following is a specification, reference being had to the accompanying drawing, forming part thereof.

In the drawing:

Fig. 1 is a front view of a sash weight suspension pulley cover embodying my new design;

Fig. 2 is a side view of the sash weight suspension pulley cover of Fig. 1;

Fig. 3 is a longitudinal central section through the sash weight suspension pulley cover taken along the line 3—3 of Fig. 1;

Fig. 4 is a transverse section through the sash weight suspension pulley cover, taken along the line 4—4 of Fig. 1; and

Fig. 5 is a bottom view of the sash weight suspension pulley cover.

I claim:

The ornamental design for a sash weight suspension pulley cover, substantially as shown.

JOSEPH NIEDERMEYER.
